Primary Examiner — Jennifer L Watkins*Assistant Examiner* — Samantha Lynne Brodowski(57) **CLAIM**

The ornamental design for a wallet, as shown and described.

DESCRIPTION

FIG. 1 is a front, right and top perspective view of a wallet showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a top, right and front perspective view of the wallet of FIG. 1, shown in condition of use;

FIG. 10 is a perspective view of the wallet in a unfolded state; and,

FIG. 11 is another perspective view of the wallet in a unfolded state.

The portions of the wallet shown in broken lines in FIGS. 1-11 do not form part of the claimed design. The broken line showing of the card in FIG. 9 is for the purpose of illustrating portions of the environmental structure and forms no part of the claimed design.
